SYSTEM AND MEANS OF CONTROL.

1,156,841.

Specification of Letters Patent. Patented Oct. 12, 1915.

Application filed July 16, 1914. Serial No. 851,379.

To all whom it may concern:

Be it known that we, JOHN S. HADDEN and FREDERICK H. JOHNSON, both citizens of the United States, residing at Huntington Park and South Pasadena, in the county of Los Angeles and State of California, respectively, have jointly invented new and useful Improvements in Systems and Means of Control, of which the following is a specification.

This invention relates to systems and means of control, and it has for its object to provide improvements of this character applicable to a wide range of mechanisms, devices, apparatus and things, and adapted for use throughout a wide range of service and in various and sundry arts and branches of industry, and whereby a traveling actuator may successively actuate, energize, move or set into motion or activity, a plurality or series of such apparatus, devices or other things, all responsive to predetermined conditions with respect to periodicity or time inter-relation, and likewise with respect to extent or duration of action of the controlled device or feature.

The invention has for its further object the provision of the improvements of the character stated which will be superior in point of relative simplicity and inexpensiveness of construction and organization, convenience and facility in installation, operation and control, positiveness in action and reliability and durability, freedom from likelihood to get out of repair, and adaptability to the general conditions of service in connection with which it is to be installed or employed, and which will be generally superior in efficiency and serviceability.

With the above and other objects in view, the invention consists in the novel and useful provision, construction, combination, formation, relative arrangement and interrelation of features, parts, elements, members and organisms, hereinafter generally as well as particularly described, shown in the drawings and finally pointed out in claims.

In the drawings: Figure 1 is a diagrammatic view of a system and means of control embodying the invention, the same being shown specifically as applied and adapted for controlling the successive actuation of lawn sprinklers or the like; Fig. 2 is an enlarged detail longitudinal sectional view

taken on the line x^2-x^2 , Fig. 3, and looking 55 in the direction of the appended arrows; Fig. 3 is a similar enlarged detail view taken on the line x^3-x^3 , Figs. 1 and 2, and looking in the direction of the appended arrows; Fig. 4 is an enlarged fragmentary elevation of a modified form of construction and organization of a part of the system and means disclosed in the first three figures, providing for a return transit of the actuator; and, Fig. 5 is an enlarged detail longitudinal sectional view taken upon the line x^6-x^6 , Fig. 1, and looking in the direction of the appended arrows.

Corresponding parts in all the figures are designated by the same reference characters.

Referring with particularity to the drawings, in which we have shown but one specific embodiment of the improved system and means of control constituting the invention, and which is merely an exemplary showing 75 and not intended in the least to establish any metes or bounds for the invention in its general aspects and wide range of adaptability as above pointed out, A in Fig. 1 and B in Fig. 4 designate, in each instance, a circuit 80 traversed by an actuator C, shown in Figs. 4 and 5, which controls a plurality of devices shown as lawn sprinklers D which are arranged in a series in a predetermined and selected relation, and which are visited successively or in accordance with a predetermined scheme of visitation by the actuator C which sets the sprinkler into operation, causing such operation to be maintained for a predetermined period of time, and, after 90 the lapse of a predetermined period of time, passes to the next of series of sprinklers and acts as desired or required in connection therewith. The circuit A is shown as a closed circuit, that is a circuit the ends of 95 which are brought together at a common end station a shown in Fig. 1 and in detail disclosed in Figs. 2 and 3. In Fig. 4 the circuit B is shown as having separated end portions, whereby the actuator does not return to a given starting point, but is introduced within the circuit at one end of the circuit, as b, and withdrawn from the same at the other end, as c.

The circuit A may consist of a conduit or 105 pipe 6 which is broken at the several stations d adjacent to the respective sprinklers D; each of such stations including suitable

controlling means whereby the respective sprinkler is actuated. It will be understood that the circuit B, which may likewise consist of a suitable conduit or pipe 7, is to 5 similarly include a plurality of the stations *d* which are arranged respectively adjacent to the several sprinklers D. The actuator C, in each instance, may be articulated in form and consist of two or more bodies or 10 projectiles or torpedoes 8 linked together as at 9, or of a single body, such plurality of linked bodies being provided so that the total actuator may conveniently round any curves or corners in the circuit, and hence be 15 more adaptable to the circuit 6. In the non-continuous circuit B this actuator is inserted within the conduit 7 at one end or station, *b*, after the removal of an end cap 10, and is 20 carried through the conduit by water or other fluid entering such conduit adjacent to the station *b* through a supply pipe 11. The actuator is removed from the other end of the conduit 7 after the removal of an end cap 12 in the station *c*. An outlet is 25 provided in the conduit 7 at the station *c* through a drain pipe 13.

The station *a* in the closed circuit A is installed in an interruption in the conduit 6, and includes in its organization and provision 30 a cylinder 14 with opposite ends of which the ends of the interrupted conduit 6 are connected, eccentrically, such cylinder having an actuator housing 15 closely fitting within the cylinder and having two separate 35 chambers 16 and 17 adapted to respectively register with the ends of the interrupted conduit 6, in accordance with oscillatory adjustment of the housing within the cylinder; said housing having a projecting arm 18 accommodated in its movement by a segmental 40 slot 19 in the cylinder 14, and by which arm such housing may be adjusted. Each chamber 16 and 17 is provided with a port 20 adapted to register with a fluid inlet port 21; and each chamber 16 and 17 is provided with 45 a fluid drain port, 22 and 23, respectively, which ports are adapted to alternately register with a fluid drain pipe 24. The ports 22 and 23 are arranged at one end of the 50 housing 15 and the ports 20 are arranged at the other end of said housing. The slot 19 is conveniently provided by forming the cylinder 14 in halves which are bolted together, as at 25.

In assembling the parts, the actuator C is introduced within the housing 15, as within 55 the chamber 17. When such housing is turned to bring the actuator up into registration with the end of the conduit 6 shown in the drawing in registration with the chamber 16, fluid is admitted through the supply pipe 21 and the port 20 and the actuator traverses the conduit 6 and finally returns 60 through the same to the chamber 16 where it is brought to rest by the end of the cylinder,

closing the drain through the pipe 24. The fluid is now shut off at the pipe 21. When it is desired to again start the actuator upon its circuit, the housing 15 is again turned by the arm 18 and the actuator, now in the 70 chamber 16, is brought up so that the chamber 16 is in the position shown in the drawings, whereupon fluid is again admitted through the port 20 to the chamber 16 and the actuator again traverses its circuit. 75 When the actuator arrives at one of the stations *d*, it operates upon the controlling means *f* therein installed, to operate the respective sprinkler D, dwelling for a predetermined period of time at such station, and 80 then passing on to the next succeeding station *d*.

The controlling means *f* are shown as comprising a piston 26 mounted to play within a cylinder 27, the opposite ends of which communicate with the ends of the interrupted conduit 6, such conduit being so interrupted to include the station *d* and the controlling means thereof. The piston is provided with a bore 28 which communicates 90 with the portions of the conduit 6 and which is traversed by the actuator C. Connected with one end of the piston is a packed rod 29 operatively connected with a centrally pivoted rocking arm 30 the other end of 95 which is operatively connected with the packed stem 31 of a piston 32 playing within an auxiliary cylinder 33 mounted upon the cylinder 27; such rod 31 being formed at one end into a toothed rack 34 adapted 100 to mesh with a mutilated pinion 35 fixed to the stem 36 of a valve controlling the flow of water to the sprinkler device D. Such water is supplied to such device, and to each of such devices, by a supply pipe 37 which 105 parallels the conduit 6 of the circuit *a* and is supplied with water from any suitable source. As the stem 31 plays it opens or closes the valve upon the stem 36 in accordance with any desired rate of timing. The 110 other end of the piston 26 is provided with a head 26^a which co-operates with a dashpot 38 at the corresponding end of the cylinder 27; such dashpot having a by-pass 39 communicating with the cylinder at one end 115 and with the inner end of the dashpot at the other end; the flow of fluid through such by-pass being regulated by an adjusting screw 40 upon the dashpot. Within the head 26^a is formed a chamber 26^b communicating with a duct 26^c controlled by a check valve 26^d, permitting flow of fluid from the cylinder 27 into the dashpot as the head 26^a recedes from the dashpot, and preventing flow of fluid through the duct 26^c when the head is entering or moving inwardly of the dashpot. The piston 26 is further provided with a vertically playing stem 40^a carrying a beveled head 41 normally depressed by a spring 42, such head and spring 42 being 120 125 130

accommodated in a chamber in the piston; and the lower end of the stem 40^a normally intrudes within the bore 28 and projects within the path of transit of the actuator C 5 through such bore. An adjustable trip device consisting of a screw 43 is threaded in the end of the cylinder which is provided with a dashpot, the beveled nose 44 of the same being disposed in the path of movement of the head 41 when such head moves 10 jointly with the piston.

With the parts in the positions shown in Fig. 5, when the actuator enters the bore 28, it strikes the lower intruding end of the 15 stem 40^a, carrying the piston, which with its parts moves in a liquid bath in the cylinder 27, in the direction of the dashpot. As the head 26^a enters the dashpot the movement of the piston is retarded, being phased in accordance with the rate of flow of fluid 20 through the duct 39 subject to the control of the adjusting screw 40. When this progress of the piston has brought the nose 44 into engagement with the beveled head 41, the 25 stem 40^a is raised, releasing the actuator which is carried by the fluid in the conduit 6 cut off of the bore 28 and on farther through the conduit 6, and so to the next station d. During the movement of the piston 26 as 30 last recited, the stems 29 and 31 move to open the valve upon the stem 36, thereby setting the sprinkler device in operation. The piston 32, of course, moves toward the right-hand extremity of the cylinder 33. A 35 by-pass 45 is provided between the conduit 6 beyond the end of the cylinder 27 provided with a dashpot 38, and the far end of the cylinder 33. When the actuator has passed the by-pass 45, power fluid in the conduit 6 40 enters such by-pass and flows into the cylinder 33, moving the piston 32 and the stem 31 so as to close the valve upon the stem 36 and terminate the action of the sprinkler device. This action, through the stems 31 and 45 29 and the lever 30, restores the piston 26 to the position shown in the drawings, the head 26^a being withdrawn from the dashpot 38, which action is permitted by the flow of fluid from the cylinder 27 through 50 the duct 26^c and past the check valve 26^d and into the dashpot. Upon the succeeding action of the piston 26 to set the sprinkler device D into operation, the fluid in the cylinder 33 is evacuated through the by-pass 45 55 and into the conduit 6, from which pressure is removed by stoppage of such conduit by means of the actuator C within the bore 28.

It will be noted that whether the non-continuous circuit B or the continuous circuit 60 A is employed, the operation of each of the controlling means F in each station d will be the same, and as described.

The difference in action as between the two circuits, with respect to the actuator, 65 that is with respect to initiating the transit

of the actuator, as above pointed out, the actuator in one instance always remaining within the closed circuit, and being shifted from its position at the end of the transit to its position to begin transit of the circuit 70 bv adjusting the housing 15 in the cylinder 14 through the agency of the arm 13; whereas in using the circuit B, the actuator is simply taken from the end c of the circuit, by removing the cap 12, and is re-introduced 75 into such circuit at the end b thereof, after removal of the cap 10.

It is manifest that many changes may be made in the provision, construction, formation, association and relative arrangement 80 of features, parts and members in adapting the invention to varying services in the various arts and branches of industry or conditions of service to which the invention is applicable, as above stated, all without departing from the spirit of the invention. 85

Having thus disclosed our invention, we claim and desire to secure by Letters Patent:

1. An improved system and means of control, comprising a plurality of separate operative devices; an actuator, and means for causing the actuator to independently visit said devices and actuate the same; means being provided whereby the period of each actuation may be varied by independently 90 varying the period of dwell of the actuator at each of said devices.

2. Improvements of the character disclosed, comprising a plurality of separate devices; a plurality of separate controlling 100 means, one for each of said devices, an actuator, and means for causing the actuator to independently visit and operate upon said separate controlling means; said latter means comprising a fluid circuit within 105 which the actuator traverses under pressure applied to the fluid thereof; each of said separate controlling means comprising a cylinder, a piston therein, stop means carried by the piston and normally disposed in the path of the actuator, and means withdrawing said last named means from the path of the actuator, upon a predetermined 110 movement of the piston.

3. Improvements of the character disclosed, comprising a plurality of separate devices, a plurality of separate controlling means, one for each of said devices, an actuator, and means for causing the actuator to independently visit and operate upon said 115 separate controlling means; said latter means comprising a fluid circuit within which the actuator traverses under pressure applied to the fluid thereof; each of said separate controlling means comprising a cylinder, a piston therein, stop means carried by the piston and normally disposed in the path of the actuator, and means withdrawing said last named means from the path of the actuator, upon a predetermined movement of the 120 piston.

piston; said last named means being adjustable.

4. Improvements of the character disclosed, comprising a plurality of separate devices, a plurality of separate controlling means, one for each of said devices, an actuator, and means for causing the actuator to independently visit and operate upon said separate controlling means; said latter means comprising a fluid circuit within which the actuator traverses under pressure applied to the fluid thereof; each of said separate controlling means comprising a cylinder, a piston therein, stop means carried by the piston and normally disposed in the path of the actuator, and means withdrawing said last named means from the path of the actuator, upon a predetermined movement of the piston; said cylinder being provided with a dashpot which co-operates with said piston to vary the rate of motion thereof.

5. Improvements of the character disclosed, comprising a plurality of separate devices, a plurality of separate controlling means, one for each of said devices, an actuator, and means for causing the actuator to independently visit and operate upon said separate controlling means; said latter means comprising a fluid circuit within which the actuator traverses under pressure applied to the fluid thereof; each of said separate controlling means comprising a cylinder, a piston therein, stop means carried by the piston and normally disposed in the path of the actuator, and means withdrawing said last named means from the path of the actuator, upon a predetermined movement of the piston; said cylinder being provided with a dashpot which co-operates with said piston to vary the rate of motion thereof; said controlling means further including a supplementary cylinder, a piston therein, and a by-pass between the cylinder and the fluid circuit.

6. Improvements of the character disclosed, comprising a plurality of separate devices, a plurality of separate controlling means, one for each of said devices, an actuator, and means for causing the actuator to independently visit and operate upon said separate controlling means; said latter means comprising a fluid circuit within which the actuator traverses under pressure applied to the fluid thereof; each of said separate controlling means comprising a cylinder, a piston therein, stop means carried by the piston and normally disposed in the path of the actuator, and means withdrawing said last named means from the path of the actuator, upon a predetermined movement of the piston; said cylinder being provided with a dashpot which co-operates with said piston to vary the rate of motion thereof; said dashpot being provided with a

by-pass and with means for varying the rate of flow of fluid through said by-pass.

7. Improvements of the character disclosed, comprising a plurality of separate devices, a plurality of separate controlling means, one for each of said devices, an actuator, and means for causing the actuator to independently visit and operate upon said separate controlling means; said latter means comprising a fluid circuit within which the actuator traverses under pressure applied to the fluid thereof; each of said separate controlling means comprising a cylinder, a piston therein, stop means carried by the piston and normally disposed in the path of the actuator, and means withdrawing said last named means from the path of the actuator, upon a predetermined movement of the piston; said cylinder being provided with a dashpot which co-operates with said piston to vary the rate of motion thereof; said piston being provided at the portion thereof which enters the dashpot with a duct for supplying fluid to the dashpot upon the withdrawal of the piston therefrom, and with a check valve in such duct.

8. In improvements of the character disclosed, a closed fluid circuit interrupted to include a cylinder, said cylinder, an actuator adapted to traverse said circuit, a housing for said actuator adjustable in said cylinder and provided with two chambers, said circuit communicating at opposite ends of said cylinder and eccentrically, and means for introducing fluid to a chamber in said housing, said cylinder serving as a stop for the actuator at the end of the circuit whereby said housing requires to be adjusted to re-introduce the actuator to the circuit and free the actuator for re-traverse of the circuit.

9. In improvements of the character disclosed, a closed fluid circuit interrupted to include a cylinder, said cylinder, an actuator adapted to traverse said circuit, a housing for said actuator adjustable in said cylinder and provided with two chambers, said circuit communicating at opposite ends of said cylinder and eccentrically, and means for introducing fluid to a chamber in said housing; said cylinder serving as a stop for the actuator at the end of the circuit whereby said housing requires to be adjusted to re-introduce the actuator to the circuit and free the actuator for re-traverse of the circuit; said cylinder being likewise provided with a drain opening adapted to communicate with a chamber in said housing.

10. In improvements of the character disclosed, a closed fluid circuit interrupted to include a cylinder, said cylinder, an actuator adapted to traverse said circuit, means for introducing fluid within said cylinder, said circuit communicating with said cylinder at a plurality of points, and means in part

within the cylinder for directing the actuator when received within said cylinder to said circuit for re-traverse of the same, said cylinder checking the actuator on completion of said circuit.

11. Improvements of the character disclosed, comprising an operable device, controlling means for said device, an actuator, and means for causing the actuator to visit and operate upon said controlling means; said causing means comprising a fluid circuit which the actuator traverses under pressure applied to the fluid therein; said controlling means comprising a cylinder, a pis-

ton therein, stop means carried by the piston and normally disposed in the path of the actuator, and means for withdrawing said last named means from the path of the actuator upon a predetermined movement of the piston.

In testimony whereof, we have signed our names to this specification in the presence of two subscribing witnesses.
